ABSTRACT

An electronic timepiece electronically driven and comprising an electronic circuit formed in a monolithic chip. This electronic circuit comprises passive elements whose resistance element is a MOS-R (metal-oxide-silicon resistor) and whose capacity element is a semiconductor element of MO'AOS (metal-oxide-Al₂O₃ oxide-silicon) construction and comprises an active element composed of a bipolar type transistor, and is formed entirely in the monolithic chip.

FIG. 9

ELECTRONIC TIMEPIECE

BACKGROUND OF THE INVENTION

1. Field of the Invention

This invention relates to an electronic timepiece such as a balance-hairspring-driven electronic timepiece, tuning fork or sound-piece-driven electronic timepiece or crystal oscillator electronic timepiece comprising an electronic circuit formed in a monolithic chip without using any other electronic parts.

2. Description of the Prior Art

An electronic timepiece heretofore proposed comprises an electronic circuit which must be provided with a plurality of electronic parts inclusive of a semiconductor chip.

In FIG. 1 is shown an electronic circuit of a balance-hairspring-driven electronic timepiece heretofore proposed. In FIG. 1, Q designates a transistor, R a base bias resistor, C a condenser for defining a time constant, C_x a condenser adapted to prevent an abnormal oscillation, L_s a detecting coil, L_d a balance-hairspring-driving coil, and V_{DD} an electric power source.

In the bipolar type transistor, in general, a forward direction voltage between the base and the emitter is 0.4 to 0.5V when a small current flows therethrough. This bipolar type transistor is designed such that a necessary bias voltage applied to its base causes the forward direction voltage to increase, to an active region from a minute amplitude. This role is played by the resistor R and the condenser C in the electronic circuit shown in FIG. 1. As seen from the above, in the conventional electronic circuit, a time constant circuit composed of the resistor R and the condenser C produces the base bias voltage in response to the amplitude of the balance hairspring so as to maintain the amplitude at a constant value. The condenser C_x plays the role of constituting a bypass for preventing the abnormal oscillation of the electronic circuit.

In the electronic circuit shown in FIG. 1, the practical value of the condenser C is C=0.47 μ F, the practical value of the resistor R is R=10 M Ω and C_x=200pF. These practical values of the condenser C and the resistor R are determined by the balance hairspring driving frequency 5 to 6 Hz (period 0.2 second). In addition, the time constant CR is given by CR=0.47 $\times$ 10⁻⁶ $\times$ 10 $\times$ 10⁶ = 4.7 sec., that is, about 25 times the balance hairspring driving period.

If the condenser is formed in the same one semiconductor chip as the transistor, the space required becomes so large that, in practice, the upper limit of the capacity of the condenser is several hundreds pF. As a result, if it is desired to make the capacity value of the condenser C small, with the product of the condenser C and the resistor R kept constant, the resistor R must necessarily be large in value. Too large a resistor R, however, results in a limitation of the base current of the transistor. As a result, it becomes difficult to obtain a sufficiently large collector current, that is, a balance hairspring driving current even if use is made of a transistor having a large amplification factor. In addition, even if a desired valve condenser were formed in a semiconductor chip, it is difficult to obtain the value of the resistor R=10M Ω where use is made of the general diffusion resistor, because the resistance value of diffusion resistors is limited to at most several tens K Ω to 100K Ω because of restrictions in the available area. As a result, it is practically impossible to form the transis-

tor, condenser and resistor of the balance hairspring driving type electronic timepiece as such shown in FIG. 1 all in a monolithic chip. Thus, use must be made of a plurality of electronic parts in order to construct the electronic circuit shown in FIG. 1. In practice, therefore, the transistor, condenser and resistor are individually connected to printed wiring formed on a ceramic substrate so as to form a mixed integrated circuit.

Such mixed integrated circuit composed of a plurality of electronic parts, however, has the disadvantages that the circuit is large in volume, that the overall reliability of the circuit is decreased with the increase of the number of the electronic parts, and that the manufacturing cost becomes high due to the increase of the number of assembling steps.

In general, the resonance frequency of an oscillating body is a function of the amplitude of the oscillation of the oscillating body. When an oscillating body is used as a speed governor, it is desired to cause the oscillating body to always oscillate with a constant amplitude. The amplitude of the oscillation of the oscillating body reaches to a steady state at a point at which the driving energy which is the function of the amplitude of the oscillation of the oscillating body balances with the lost energy of the oscillating body. Under such conditions much of the electric power is consumed so that such oscillating bodies are seldom used with a timepiece.

In general, the relation in function between the amplitude and the driving energy is so changed that the amplitude of the oscillating body becomes the steady state at a defined amplitude.

As described above with references to FIG. 1, the method heretofore proposed exclusively makes use of the fact that the diode in the forward direction between base-emitter and between base-collector of the bipolar transistor is capable of clamping a detecting signal to produce a direct current component, that the condenser is charged with the direct current component thus produced, and that the apparent bias voltage supplied to the input part of the transistor is decreased in response to the increase of the amplitude of the oscillating body, thereby decreasing the driving pulse width. This method, however, is required to maintain the applied direct current component for a time longer than the period of the oscillating body, and as a result, the time constant of discharging the condenser must be large. Thus, it is necessary to use a resistor having a large resistance value and a condenser having a large capacity. In the present semiconductor technique, it is almost impossible to manufacture the above described high ohmic resistor and large capacity condenser. As a result, an electronic circuit for use in electronic timepieces and including such high ohmic resistor and large capacity condenser could not be realized.

SUMMARY OF THE INVENTION

This invention obviates the above described disadvantages of the conventional electronic timepiece and for this purpose an electronic circuit is formed in a monolithic chip.

An object of the invention, therefore, is to provide an electronic timepiece which comprises an electronic circuit formed in a monolithic chip, and which can make the electronic circuit small in volume and can make the number of the parts included therein small, thereby improving the overall reliability in operation of the electronic circuit.

The invention provides an electronic timepiece which makes use of a signal corresponding to the differentiation of a detecting signal so as to control the bias potential supplied to the input part of an amplifier and which can control the amplitude of an oscillating body immediately before a driving pulse is obtained such that the requisite time constant is considerably smaller, thereby obviating the need for a large capacity condenser.

The invention also provides an electronic timepiece comprising an electronic circuit which includes passive elements whose resistor element is composed of MOS-R (Metal-Oxide-Silicon - - Resistor) and whose capacity element is composed of a semiconductor of MO'AOS (Metal-Oxide-Al₂O₃-Oxide-Silicon) construction and an active element consisting of a bipolar type transistor, and which can provide a combination of a high resistance resistor element, a capacity element having an excellent voltage-capacity characteristic within an operating range, and a bipolar type transistor, which is difficult to obtain by the prior art technique of manufacturing a semiconductor.

BRIEF DESCRIPTION OF THE DRAWING

FIG. 1 is an electronic circuit diagram of a conventional balance-hairspring-driving type electronic timepiece;

FIG. 2 is a block diagram illustrating the construction according to the invention;

FIG. 3 is a signal waveform diagram illustrating the operation of the construction shown in FIG. 2;

FIG. 4 is a signal waveform diagram illustrating the operation of another embodiment of the invention;

FIG. 5 is an electronic circuit diagram of an embodiment of the invention;

FIG. 6 is a perspective view of a MOS (Metal-Oxide-Silicon) transistor used in the electronic circuit shown in FIG. 5, a part being shown in section;

FIG. 7 is a partial longitudinal sectional view of a MO'AOS construction used in the electronic circuit shown in FIG. 5;

FIG. 8 is a graph showing a voltage-capacity characteristic of a semiconductor;

FIGS. 9 (1) to 9(11) are cross-sectional views of a portion of the electronic circuit according to the invention illustrating successive manufacturing steps thereof.

DETAILED DESCRIPTION OF THE INVENTION

FIG. 2 shows a circuiting block diagram form illustrating the construction according to the invention. Reference numeral 1 designates an amplifier. The driving signal transmitted by the output end of the amplifier 1 is supplied through an electro-mechanical transducer 2 to an oscillating body 3. In addition, the displacement or angular velocity component of the oscillating body 3 is fed back as an electric detecting signal through a mechanical-electric transducer 4 to the input part of the amplifier 1. The detecting signal fed back to the input part of the amplifier 1 is also supplied as a control signal through a control device 5 having both a differentiating function and an amplifying function to the input bias part of the amplifier 1.

An embodiment of the invention will now be described with reference to the signal wave diagram shown in FIG. 3 and illustrating the operation of the construction shown in FIG. 2.

In FIG. 3 A(a) is shown the embodiment of obtaining the detecting signal corresponding to the angular velocity of the overall period of the oscillating body 3. Let it be assumed that the detecting signal $f(A)$ obtained is in its steady state. Its differentiated wave $f'(A)$ is shown in FIG. 3 A(b). From this differentiated wave $f'(A)$ is obtained a control signal for the time τ_c at which the differentiated wave $f'(A)$ exceeds the threshold level Thc of the control device 5. If the control signal from 10 the control device 5, for example, causes the bias potential at the input part of the amplifier 1 to go completely to zero, this bias potential has a low level during the time τ_c and then increases towards the initial bias level with the time constant of the input part of the amplifier 1 as shown by broken lines V_B in FIG. 3A(c). To this bias potential is added the detecting signal delivered from the mechanical electric transducer 4 in an alternating current to produce a resultant potential shown by a full line in FIG. 3 I(c). From this resultant potential is obtained a driving signal pulse for that time τ_p at which the resultant potential exceeds the threshold level Thp of the amplifier 1 shown by broken lines in FIG. 3A(c).

If the amplitude of the oscillating body 3 becomes smaller, the width τ_p of the driving pulse is increased as shown in FIG. 3B, and as a result, to the oscillating body 3 is applied a larger driving energy whereby the amplitude of the oscillating body 3 is increased.

On the contrary, if the amplitude of the oscillating body 3 becomes too large, the width τ_p of the driving pulse is decreased as shown in FIG. 3 C or eventually ceased to exist, and as a result, to the oscillating body 3 is applied a smaller driving energy whereby the amplitude of the oscillating body 3 is decreased or restricted.

A ratio of the change in the driving pulse width τ_p to the variation in the amplitude of the oscillating body 3 in and about its steady oscillating state may be changed by the time constant of the input part of the amplifier 1, by the level t_0 shown in FIG. 3 B at which the control signal becomes zero and the direct current bias level begins to raise, by magnitude of the detecting signal and the like. Thus, a selection of variables of respective parts of the construction according to the invention makes it possible to obtain an optimum ratio of the change in the driving pulse τ_p to the variation in the amplitude of the oscillating body 3. As seen from the above, the invention is capable of controlling the driving pulse just prior to obtaining it, thereby obtaining the object aimed at with the aid of extremely small time constant.

Another embodiment of intermittently obtaining the detecting signal will now be described with reference to FIG. 4.

In the present embodiment, the driving signal is obtained at those portions h_1 , h_2 and h_3 of the intermittent detecting signal $f(A)$ which correspond to the tops of the detecting signal wave $f(A)$ shown in FIG. 4(a). The control signal is obtained at those portions of the intermittent differentiated wave $f'(A)$ which correspond to positions shown by h_7 and h_8 in FIG. 4(b). As a result, the driving signal is controlled at, at least, two points h_2 and h_3 , thereby significantly improving the efficiency.

If the driving signal is controlled at points h_4 , h_5 and h_6 , for example, respectively, the driving signal is over controlled at the point h_2 such that a sufficiently large driving energy can not be applied to the oscillating body 3 at its starting time. It is a matter of course that

if the driving signal is controlled at the point h_4 only, a sufficient control can not be effected of the driving signal at the point h_3 . At the other points, the driving signal is controlled in the manner similar to the above.

FIG. 5 shows an electronic circuit for controlling the driving signal.

Referring to FIG. 5, Q_1 , Q_2 and Q_3 designate transistors for constituting an amplitude control circuit, Q_4 to Q_{11} transistors for constituting amplifier and driving circuits, and L_S a detecting coil. The minute detecting voltage obtained from the detecting coil L_S is applied through a condenser C_2 to the amplifier circuit. A voltage amplification of this minute detecting voltage is effected by the transistors Q_4 to Q_9 and a current amplification thereof is effected by the transistors Q_{10} and Q_{11} , thereby operating a driving coil L_D . The voltage for driving the driving coil L_D is fed back through a resistor R_9 to the input part of the amplifier circuit. The resistor R_9 and the condenser C_2 constitute a time constant circuit which is capable of applying a bias voltage to the base of the transistor Q_4 .

The minute detecting voltage obtained from the detecting coil L_S is also applied through a differentiating network condenser C_1 to the base of the transistor Q_1 of the amplitude control circuit whose transistor Q_2 serves to amplify this detecting voltage. When detecting voltage thus amplified exceeds a given value, the transistor Q_3 becomes conductive to change the bias voltage supplied to the base of the transistor Q_4 . The use of measures described above ensures a more positive control of the amplitude of the balance hairspring of the timepiece than the base bias control circuit composed of the condenser C_2 and the resistor R_9 only and further provides the important advantage that the consumed current becomes small.

In the electronic circuit shown in FIG. 5, the maximum capacity of the condenser C_2 may be made 200 pF. As a result, such maximum capacity may be obtained by the capacity of a semiconductor. The resistance value of the resistor R_9 must be made on the order of 1000 M Ω which could not be obtained in practice by customary diffused resistors. The invention makes use of MOS-R (Metal-Oxide-Silicon-Resistor) technique in order to obtain the resistor R_9 whose resistance value is on the order of 1000 M Ω .

An electronic circuit adapted to drive the hairspring balance and formed in a monolithic chip on the basis of the MOS-R technique and a method of manufacturing it will now be described with reference to FIGS. 6 to 9.

In principle, the MOS-R (Metal-Oxide-Silicon) technique makes use of a non-linear voltage-current characteristic exhibited between two terminals of a depletion type MOS (Metal-Oxide-Silicon) transistor (abbreviated as MOST) having a gate of P channel MO'AOS (Metal-Oxide-Al₂O₃-Oxide Silicon) construction as a highly resistive resistor whose resistance value is on the order of 1000 M Ω , one of the two terminals being a drain region and the other terminal being a source region short-circuited to a substrate of semiconductor material and a gate.

The invention makes use of a method of manufacturing MOST comprising a step of incorporating a highly resistive resistor into a silicon chip which is the same as a bipolar transistor shown in FIG. 6.

Referring to FIG. 6, reference numeral 6 designates a source, 7 a gate, 8 a drain, 9 an oxide film, and 10 a N type substrate.

In order to use MOS-R (Metal-Oxide-Silicon-Resistor) as a highly resistive resistor, MOST (Metal-Oxide-Silicon Transistor) must be provided with a gate of P channel MO'AOS (Metal-Oxide Al₂O₃-Oxide Silicon) construction as will be described.

In FIG. 7 is shown a MO'AOS (Metal-Oxide-Al₂O₃-Oxide-Silicon gate composed of five layers consisting of an aluminum electrode M, a protective oxide film O', an alumina film A, a first layer oxide film O and a silicon substrate S viewed from the above. The silicon substrate S is of N conductivity type and the first layer oxide film O is a SiO₂ film thermally oxidized on the silicon substrate S. The thickness of this thermally oxidized film O is capable of controlling the resistance value of the MOS-R.

An example between the thickness of the thermally oxidized film O and the resistance value of the MOS-R (Metal-Oxide-Silicon Resistor) is shown in the following Table.

TABLE

Thickness of thermally oxidized film	Resistance value (voltage across terminals 1.5V)
0 A	$1 \times 10^6 \Omega$
100 A	$5 \times 10^6 \Omega$
200 A	$2 \times 10^7 \Omega$
300 A	$5 \times 10^7 \Omega$
400 A	$1.5 \times 10^8 \Omega$
500 A	∞

In the above Table, the specific resistance of the N type silicon substrate is 5 Ω -cm, the thickness of the alumina film is 2000 A, the thickness of the protective SiO₂ film is 1000 A, and W/L of the MOS-R (Metal-Oxide-Silicon-Resistor) is 1/200 (W is a width of the gate 7 and L is its length as shown in FIG. 6).

In general, the thickness of the alumina film A has less influence upon the resistance value of the MOS-R (Metal-Oxide-Silicon-Resistor). It is preferable to treat the alumina film A at a low temperature, because a high temperature treatment causes the alumina film to be hardened which must be avoided if an etching treatment is to be used. The protective SiO₂ film O' is deposited from a vapor phase on the alumina film A. As described above, the alumina film A is subjected to the low temperature treatment so as to easily effect the etching treatment. The alumina film A subjected to the low temperature treatment is liable to be extremely sensitive to after treatments.

For example, if the alumina film A is formed by thermally decomposing aluminum isopropylate or aluminum ethylate at a temperature lower than 800°C, there is a risk of the alumina film A thus formed being easily affected by an etching bath used in the etching treatment of forming contact holes or etching aluminum. In the present invention, in order to avoid such disadvantage, the alumina film A is covered with the protective SiO₂ film O' deposited thereon from vapor phase.

The P channel MOST (Metal-Oxide-Silicon Transistor) having the MO'AOS (METAL-OXIDE-Al₂O₃-OXIDE-SILICON) gate constructed as above described is of depletion type. As shown in the above Table, if the thickness of the first SiO₂ film is larger than 500 A, the resistance value becomes infinitely large so

that the MOST becomes enhancement type in which no current flows. As a result, provision may be made of a MO'AOS gate having a resistor portion upon the completely exposed silicon surface and the other portions having excess oxide of a thickness of at least 500 Å, no current flows through the MO'AOS. In addition, the gate portion of the MOS-R may be used as a condenser.

The invention makes use of a N channel type semiconductor capacity characteristic by taking its capacity-voltage characteristic (C-V characteristic) into consideration. That is, the N channel type semiconductor capacity incorporated at the time of manufacturing the MOST-R is of enhanced type having a good C-V characteristic in the operating voltage range shown in FIG. 8.

A method of manufacturing the electronic circuit embodying the invention shown in FIG. 5 will now be described.

Constitutional elements formed in a monolithic chip (silicon chip in the present embodiment) are a NPN bipolar transistor, a PNP lateral bipolar transistor, a MOS-R of P channel MO'AOS construction, and a condenser of N channel MO'AOS construction. Steps of manufacturing these constitutional elements will now be described with reference to FIG. 9.

As shown in FIG. 9(1), a P type silicon is thermally oxidized to form an oxide layer and the oxide layer thus formed is etched to cut a given number of holes. Then, a donoer element compound having a small thermal diffusion constant such as antimony and the like is diffused into the P type silicon. Reference numeral 31 designates a N⁺ layer thus diffused into the P type silicon and usually called as an buried layer. This N⁺ layer 31 is capable of lowering the saturated collector-emitter voltage V_{ces} of the NPN transistor and of eliminating a parasitic transistor in case of using the lateral PNP transistor.

As shown in FIG. 9(2), SiO₂ grown in the step shown in FIG. 9(1) is completely removed and then a N type silicon epitaxial layer 32 is grown on the P type silicon as well as on the diffused N⁺ layers. The thickness of the N type silicon epitaxial layer 32 is larger than about 10 microns. It is necessary to make the specific resistance of the N type silicon epitaxial layer 32, 1 to 5Ω-cm in consideration of the characteristics of the transistor and MOS-R.

In the step shown in FIG. 9(3), a thermal oxidation is effected to produce an oxide film and then the oxide film thus produced is etched to form a given number of holes 33. A compound of an accepter element such as boron and the like is thermally diffused into the N type silicon epitaxial layer 32 until the thermally diffused regions reach to the surface of the starting P type silicon substrate. This step is so-called isolation diffusion and is capable of isolating the N type zones as islands surrounded by these diffused zones.

In the step shown in FIG. 9(4), the SiO₂ layer 35 formed by the step shown in FIG. 9(3) or a SiO₂ layer newly grown is subjected to a photoetching process to form a given number of holes. Through these holes is thermally diffused a compound of an accepter element such as boron and the like to form a PN junction or junctions 36 in the respective islands until the PN junction or junction 36 reach to a given depth (usually 2 to 3μ). These P type diffused zones form a base layer of the NPN transistor, a collector layer and an emitter layer of the PNP transistor, two terminals of the MOS-

R, and a lower electrode of the MOS-C (N-channel type C improves the C-V characteristic).

In the step shown in FIG. 9(5), a photoetching process is subjected to the SiO₂ layer 38 formed during the step shown in FIG. 9(4) or to a newly grown SiO₂ layer to form a given number of holes. Through these holes is thermally diffused a compound of a donner element to form a PN junction 38 until the PN junction 38 reaches to a given depth (usually 2 to 3μ). These N type diffused zones form an emitter layer and a collector contact of the NPN transistor, a base contact of the PNP transistor, and a substrate contact of the MOS-R. Particularly, the steps shown by FIGS. 9(4) and 9(5) serve to determine the electric characteristics such as 15 h_{FE} (grounded emitter current gain) and the like of the NPN transistor so that the thermal diffusion of these steps must be effected with particular care.

A feature of the invention is the provision of the above described steps of simultaneously forming in the 20 N type silicon a PNP transistor, two terminals of MOS-R and two terminals of MOS-C with a NPN transistor.

In the step shown in FIG. 9(6), the SiO₂ layer formed by the step shown in FIG. 9(5) or a newly grown SiO₂ layer is subjected to a photoetching process to form a given number of holes for the purpose of forming a 25 MOS-R and MOS-C. This step of forming the holes must be effected in a manner such that residual SiO₂ becomes absent. In addition, it is preferable to make holes at those portions of the SiO₂ layer which correspond to the contact holes for the purpose of simplifying the manufacturing steps to be effected.

In the step shown in FIG. 9(7), a growth of the first 30 SiO₂ layer is effected. For example, the first SiO₂ layer whose thickness is about 200 Å is grown by an oxidation at a temperature of 700°C for 20 minutes.

In the step shown in FIG. 9(8), the alumina film is 35 formed and a heat treatment is carried out on it. It is preferable to use an organic aluminum as an alumina source and thermally decompose it and deposit it from vapor phase. For example, aluminum isopropylate or aluminum ethylate is vaporized with the silicon substrate heated at a temperature of about 420°C to deposit the alumina film of about 2000 Å and then the alumina film thus deposited is heat-treated at a temperature of 750°C in N₂ atmosphere for about 30 minutes.

In the step shown in FIG. 9(9), the protective SiO₂ film is deposited from vapor phase. Its heat treatment has usually been effected at a temperature on the order of 900°C for the sake of safety. As above described, the alumina film treated at a high temperature causes it to be hardened which makes the etching treatment to be effected difficult. As a result, the protective SiO₂ film is heat-treated at a temperature on the order of 750°C for 30 minutes in O₂ atmosphere. The protective SiO₂ film thus being formed can sufficiently protect the alumina film from being affected by the etching bath. It is preferable to make the thickness of the protective SiO₂ film on the order of 1000 Å because the protective SiO₂ film could not protect the alumina film from being affected by the etching bath if the thickness of the protective SiO₂ film becomes too thin. In the step shown in FIG. 9(10), the etching process is effected so as to 55 form contact holes through which are led out aluminum electrodes by the next step. In the well known steps, layers to be formed with the contact holes has a multiplicity of layers composed of a protective SiO₂ film.

film, an alumina film, a first SiO_2 film, and superimposed SiO_2 films formed in the steps shown in FIGS. 9(1) to 9(5) (those SiO_2 films are absent at the MOS-R part), and as a result, the suitable etching solution must frequently be prepared.

On the contrary, the invention provides the holes for those portions corresponding to the contact holes by the step shown in FIG. 9(6) for the purpose of forming the MOS-R and MOS-C. As a result, layers of the portions corresponding to the contact holes has three layers composed of the protective a SiO_2 film, and an alumina film and a first SiO_2 film.

In case of effecting the etching process, in the first place the protective SiO_2 film is covered with a resist and then contact holes are formed in the protective SiO_2 film by acidic ammonium fluoride solution. Then, the resist is removed by $\text{H}_2\text{SO}_4 + \text{H}_2\text{O}_2$ solution. It is preferable to use KPR (Kodak Photo Resist) as the resist. When the resist is removed, the alumina film is simultaneously removed as a result a SiO_2 film having an extremely thin thickness of the order of 100 to 200 Å remains. Then, use is made of a P-etching solution whose rate of etching the SiO_2 film is low. The SiO_2 film remained on the overall surface becomes thin so that it is preferable to make the SiO_2 film which the contact holes are not formed sufficiently thick beforehand.

In the step shown in FIG. 9(11), aluminum is deposited and then subjected to the etching process to form electrodes 41.

The bipolar technique heretofore proposed determines the temperature and time necessary for the heat treatment or so-called sintering treatment by taking the sufficient alloying between aluminum and silicon into consideration and hence the heat treatment is effected at 400°C for 30 minutes.

On the contrary, in the present invention the gate part of the MOS-R must be sufficiently sintered, otherwise the resistance value of the MOS-R becomes unstable. Experimental tests have yielded satisfactory good results when the gate part is sintered at 475°C for 90 minutes. In addition, such sintering treatment does not give much influence upon the characteristic of the bipolar element.

In FIG. 9(11), reference numerals 51 and 52 designate electrode terminals of the MOS-R, 53 an electrode terminal of the P type silicon substrate, 54 an electrode terminal of the NPN transistor base, 55 an electrode terminal of the NPN transistor emitter, 56 an electrode terminal of the NPN transistor collector, 57 an electrode terminal of the PNP transistor base, 58 an electrode terminal of the PNP transistor emitter, 59 an electrode terminal of the PNP transistor collector, and 60 and 61 electrode terminals of the MOS-C.

As stated hereinbefore, the use of the electronic circuit described ensures a decrease of the capacity of the condenser to the order of 200P_F and a production of a highly resistive resistor and provides the important advantage that an electronic circuit for use in balance hairspring driving type electronic timepieces can be formed in a monolithic chip, that is, in the same single chip. The electronic timepiece formed in the monolithic chip is far superior in mass production scale, reliability, volume density, cost and the like to the conventional electronic watch composed of a multiplicity of electronic parts and the former is significantly improved in function if compared with the latter.

The monolithic chip in which the electronic circuit for use in balance hairspring driving type electronic timepieces shown in FIG. 5 was incorporated as described above may also be applied to an electronic circuit for use in tuning fork driving type electronic timepieces. In addition, the MOS-R technique described above is capable of manufacturing an electronic circuit for use in crystal oscillator type electronic timepieces. It is a matter of course that the monolithic chip permits of obtaining all types of electronic timepieces.

What is claimed is:

1. An electronic timepiece, comprising:
an electromechanical transducer for converting an electric signal into mechanical energy;
an oscillating body connected to said mechanical transducer and driven by said mechanical energy to an amplitude dependent upon the energy of a signal applied to said transducer;
a mechanical-electrical transducer coupled to said oscillating body for generating an electric feedback signal having an amplitude corresponding to the displacement of said oscillating body;
a feedback amplifier responsive to said feedback signal and connected between said mechanical-electrical transducer and said electro-mechanical transducer for applying an electrical signal to the latter, said amplifier having a variable bias;
a control circuit including a first amplifier means connected to said mechanical-electrical transducer by a differentiating means and energized by said feedback signal, said first amplifier means being connected to said feedback amplifier for varying said bias thereof, said amplifier and said control circuit being formed in a monolytic chip whereby the bias of the feedback amplifier is responsive to the differential of said feedback signal to control oscillation of the oscillating body.

2. The electronic timepiece defined in claim 1 wherein said feedback signal is an alternating current signal.

3. The electronic timepiece defined in claim 1 wherein said first amplifier includes a plurality of NPN transistors in cascade with the collector of each transistor connected to the base of a successive transistor, the base of the first transistor being energized through said first capacitor from said mechanical electrical transducer and the collector of the last transistor forming an output terminal;

said feedback amplifier includes a plurality of other pairs of NPN transistors with a first transistor of each pair having an emitter connected to the base of the second transistor of each pair and their collectors tied together and to the base of the first transistor of a successive pair, said output terminal being connected through a resistor to the base of the first transistor of the first pair and said mechanical electrical transducer being connected via a second capacitor to the base of the first transistor of the first pair;

said timepiece further including another NPN transistor having its base connected to the collector of the last transistor of the last pair, and the last NPN transistor in the last pair having its base connected to the emitter of said other transistor in the last mentioned pair, a PNP transistor having its base connected to the collector of said last mentioned transistor and said first NPN transistor in the said

feedback amplifier having a base connected to the collector of said PNP transistor and the emitter-collector electrodes of said PNP transistor in circuit with said electromechanical transducer.

4. The electronic timepiece defined in claim 3
5 wherein said circuit includes as its passive element a resistor element composed of an element whose one terminal is a drain of a depletion type MOST (Metal-Oxide-Silicon structure type transistor) and the other terminal is a connection of a source, gate and substrate 10 thereof and as a capacity element an element composed of a semiconductor element of MO-AOS (Metal-

Oxide-Al₂O₃-Oxide-Silicon) structure type, an upper metal of said semiconductor element being one terminal and an under silicon layer thereof being the other terminal.

5. An electronic timepiece as defined in claim 3
wherein said electronic circuit includes as its passive element a resistor element composed of a depletion type MOST (Metal-Oxide-Silicon structure type transistor) and includes as its active element a bipolar type 10 transistor.
